UNITED STATES PATENT OFFICE

141,996

DESIGN FOR A HUB SWITCH STAND

Charles H. Nordberg, Chicago, Ill., assignor to
Pettibone Mulliken Corporation, Chicago, Ill.,
a corporation of Illinois

Application November 25, 1944, Serial No. 116,553

Term of patent 14 years

(Cl. D66—3)

To all whom it may concern:

Be it known that I, Charles H. Nordberg, a citizen of the United States, residing at Chicago Heights, in the county of Cook and State of Illinois, have invented a new, original, and ornamental Design for Hub Switch Stands, of which the following is a specification, reference being had to the accompanying drawing, forming a part thereof.

Figure 1 is a top plan view of a hub switch stand in accordance with my new design, a por-

tion of the operating lever having been broken away for convenience of illustration;

Figure 2 is an end elevational view of the same; and

Figure 3 is a side elevational view, a portion of the operating lever having been broken away for convenience of illustration.

I claim:

The ornamental design for a hub switch stand, as shown.

CHARLES H. NORDBERG.
